PORTABLE NUCLEAR DENSITY-MOISTURE INSTRUMENT

John R. Martin, Glendale, Wis., assignor to
Soiltest, Inc., Evanston, Ill.

Filed May 11, 1971, Ser. No. 142,421

Term of patent 14 years

Int. Cl. D10—99

U.S. Cl. D52—1

FIG. 1 is a top plan view of a portable nuclear density-moisture instrument showing my new design;
FIG. 2 is a front elevational view of FIG. 1;
FIG. 3 is a rear elevational view of FIG. 1;
FIG. 4 is a bottom plan view; and
FIG. 5 is a right side elevational view of FIG. 1.
I claim:
The ornamental design for a portable nuclear density-moisture instrument, as shown.
